UNITED STATES PATENT OFFICE.

ROBERT KEYS ANDERSON, OF BLOUNTVILLE, TENNESSEE.

CAR-COUPING.

1,279,215.

Specification of Letters Patent. Patented Sept. 17, 1918.

Application filed April 2, 1918. Serial No. 226,213.

To all whom it may concern:

Be it known that I, ROBERT KEYS ANDERSON, a citizen of the United States, residing at Blountville, in the county of Sullivan and State of Tennessee, have invented new and useful Improvements in Car-Couplings, of which the following is a specification.

This invention relates to car couplings and it consists in the novel features hereinafter 10 described and claimed.

An object of the invention is to provide a car coupling of simple and durable structure the same having means whereby two 15 connected with each other and means adapted to be readily operated for permitting the coupling members to disengage from each other.

With this object in view the coupling comprises a head provided at its side portions 20 with vertically disposed slots or guides. A shaft is journaled in the guides and carries at its ends disks which are concentrically positioned thereon. A second shaft is 25 journaled at a fixed point in the lower portion of the head and at the lower ends of the slots and carries at its ends disks which are eccentrically positioned thereon and upon which the first mentioned disks rest. 30 A crank handle is provided upon the second mentioned shaft. The coupling link is provided at its upper side and in the vicinity of its ends, which are pointed, with recesses one of which is adapted to receive the upper 35 shaft in the coupling head.

In the accompanying drawings:—

Figure 1 is a longitudinal sectional view 40 of one of the coupling members. Fig. 2 is a side view.

Fig. 3 is a longitudinal section with the parts in uncoupled position.

Fig. 4 is a section on the line 4—4 of Fig. 1.

The coupling comprises a head 1 which is 45 provided with the usual throat 2 adapted to receive the end portion of a link 3. The link 3 is pointed at its opposite ends and the said link is provided at its upper side and in the vicinity of its ends with transversely 50 disposed notches 4.

The head 1 is provided at the opposite sides of the throat 2 with vertically disposed guide slots 5 and a shaft 6 is loosely received in the said slots. The shaft 6 car-

ries at its ends circular disks 7 which are 55 concentrically positioned upon the said shaft. A shaft 8 is journaled in the head 1 below the guide slots 5 and circular disks 9 are eccentrically positioned upon the shaft 5. The disks 7 rest upon the disks 9. A 60 crank handle 10 is fixed to one end of the shaft 8.

The disks 9 are of such weight that their centers of gravity will normally lie below the axis of the shaft 8. Inasmuch as the 65 disks 7 rest upon the disks 9 the axis of the shaft 6 is normally in a relatively close position to the shaft 8. When the end of the link 3 is inserted between the shafts 6 and 8 the pointed end portion of the said link will 70 lift the shaft 6 and the said shaft may turn and roll along the upper side of the link 3 until it enters the approaching notch 4, when the shaft 6 will drop into the said notch. Thus the link 3 is connected with the 75 coupling head. To uncouple the link from the head the shaft 8 is turned by using the handle 10 whereby the disks 9 are turned and the deep parts of the eccentric of which the disks 9 are component parts will move 80 above the axis of the shaft 8 and therefore the disks 7 and the shaft 6 are lifted and the shaft 6 is carried above the upper edges of the notch 4. Hence the link 3 may be 85 readily withdrawn from the coupling head.

From the foregoing description taken in conjunction with the accompanying drawings it will be seen that a car coupling of simple and durable structure is provided and that the same may be easily and quickly 90 manipulated to effect the coupling and uncoupling of two coupling members.

Having described the invention what is claimed is:

A coupling comprising a head provided 95 with a throat and having at its sides vertically disposed guide slots, a shaft loosely mounted in the guide slots, circular disks mounted upon the shaft and concentrically positioned with relation thereto, a shaft 100 journaled in the lower portion of the head and below the ends of the slots, and circular disks mounted upon the last mentioned shaft and eccentrically positioned thereon, the first mentioned disks resting upon the peripheries of the last mentioned disks.

In testimony whereof I affix my signature.

ROBERT KEYS ANDERSON.
